EXTENSION TABLE

Frederick B. Walter, Wabash, Ind., assignor to
 B. Walter & Company, Inc., Wabash, Ind., a
 corporation of Indiana

Application November 20, 1931
 Serial No. 576,252

4 Claims. (Cl. 45—113)

The object of my invention is to provide an improved extension-leaf structure for that type of tables in which a main top is rigidly carried by the leg frame, the extension leaf being nestable between the main top and big frame. My improvement is particularly useful in connection with comparatively narrow tables in that it permits the provision of two relatively wide extension leaves.

10 The accompanying drawing illustrates my invention in connection with a table, such as is useful in kitchens, having an enameled metal main top.

Fig. 1 is a transverse section with two extension leaves, one extended and the other in storage position;

Fig. 2 is a perspective of my improved metal slide bridge for a two-leaf construction;

Fig. 3 is a section on line 3—3 of Fig. 2, and 20 Fig. 4 a perspective view of a fragment of one of the extension leaves and one of the slides which carry it.

In the drawing 10 indicates a main frame supported by legs 11. This frame is of the ordinary "kitchen table" type of horizontal dimensions closely approximating those of the main top 12, which may be of any desirable construction. In the drawing this top 12 is indicated as an enameled iron plate reinforced by an under wooden frame 13. The top 12 is rigidly supported upon and above frame 10 by means of a middle cross bar 14 which bridges across the frame 10 lengthwise and which has a sufficient vertical dimension to space top 12 above the top of frame 10 an amount a trifle greater than the thickness of the extension leaves. The bridge bar 14 may be quite narrow so as to afford maximum lateral spaces for the extension leaves. In practice in a table, say 25 inches wide, the bar 14 may be in 40 the neighborhood of 3 inches in width, thus permitting extension leaves 11 inches wide.

Secured to the top of frame 10 and bridging across the same transversely beneath bar 14 are two metal slide-bridges 20 (only one being shown). Each of these slide bridges is formed of a thin metal sheet transversely slotted from its opposite ends by identical slots 21, 21, the material adjacent the slots being bent down to form stiffening flanges 22, 23. The stiffening flanges 23, 23 form the sides of a medial channel bar 24 in which is nested a wooden stiffening bar 25 secured by rivets 26 to the channel bar 24. Each flange 23 near the outer end of its slot 21 is provided with two laterally projecting pins 27 and 28.

The bounding flanges 22 and 23 of each slot 21 form guides for a slide 30, economically made of wood having a length substantially equal to the transverse inner dimension of frame 10 and each side bar of frame 10 is slotted, as at 31, 60 to admit each slide 30.

Secured to the upper edge of each slide 30 at its outer end is a leaf 32, each extension leaf being carried by two slides 30. Formed in one vertical face of each slide 30 is a groove 33 open 65 at the outer end of the slide and preferably closed at the inner end, said groove being sized to receive pins 27 and 28. The inner end of each slide 30 has its vertical dimension gradually reduced from the top downwardly and groove 33 substantially parallels the top edge of the slot. Communicating with groove 33 at an intermediate point in its length is a vertical groove 34 which, at its lower end communicates with an outwardly directed groove 35 so spaced vertically from 75 the adjacent portion of groove 33 as to be in alignment with the lower inner end of groove 33.

When the slide is in its innermost position the adjacent pins 27 and 28 lie in the outer portion of groove 33, that portion of groove 33 80 being parallel with the upper face of the extension leaf, and the extension leaf lies in storage position nested under the main top. When the extension leaf is drawn outwardly its first movement is parallel with the main top until pin 28 85 enters the downwardly trending portion of groove 33, whereupon the extension leaf is inclined downwardly as the slide is drawn to its outermost position, at which time groove 34 lies beneath pin 27, thereupon the extension leaf 90 may be raised until groove 35 is brought opposite pin 28, the extension leaf structure pivoting upon pin 28 where it has been stopped at the inner end of the lowermost portion of groove 33, and the slide structure then positioned inwardly to cause the upper wall of groove 35 to overlie pin 27, at which time the extension leaf 95 is in the plane of the main top, and the extension leaf structure moved inwardly to bring the inner edge of the extension leaf into engagement with the adjacent edge of the main top.

It will of course be understood that, if only one extension leaf is to be provided the metal slide-bridge may be considerably narrower and provided with only one slot 21.

I claim:

1. As an article of manufacture, a sheet-metal slide-bridge for extension tables, comprising, a plate having a length sufficient to bridge a table frame, a longitudinally extending vertically open 110

slot open at one end and slide-supporting elements rigid with said plate and projecting laterally into said slot.

2. As an article of manufacture, a sheet-metal slide-bridge for extension tables, comprising, a plate having a length sufficient to bridge a table frame, a longitudinally extending slot open at one end and bounded by depending flanges, and slide-supporting elements carried by one of said flanges projecting laterally into said slot.

3. As an article of manufacture, a sheet-metal slide-bridge for extension tables, comprising, a plate having a length sufficient to bridge a table frame, two longitudinally extending parallel

slots open respectively at opposite ends of the plate, and slide-supporting elements projecting laterally into each of said slots.

4. As an article of manufacture, a sheet-metal slide-bridge for extension tables, comprising, a plate having a length sufficient to bridge a table frame, two longitudinally extending parallel slots open respectively at opposite ends of the plate and each bounded by depending flanges, and slide-supporting elements carried by two of said flanges projecting laterally into each of said slots.

FREDERICK B. WALTER.
